UNITED STATES PATENT OFFICE.

FREDERICK C. RENZIEHAUSEN AND HENRY SCHUETZ, JR., OF PITTSBURG, PENNSYLVANIA.

DESIGN FOR A BOTTLE.

SPECIFICATION forming part of Design No. 25,056, dated January 21, 1896.

Application filed October 7, 1895. Serial No. 564,952. Term of patent 7 years.

To all whom it may concern:

Be it known that we, FREDERICK C. RENZIEHAUSEN and HENRY SCHUETZ, JR., citizens of the United States, residing at Pittsburg, in the county of Allegheny, State of Pennsylvania, have invented and produced a new and original Design for a Bottle; and we do hereby declare the following to be a full, clear, and exact description of the same, reference being had to the accompanying drawings, forming a part of this specification, in which—

Figure 1 is a front elevation, the lower portion being shown in section. Fig. 2 is a side elevation of the same.

The leading features of our design consist in the peculiar construction of the bottle and in the flat portions or sides provided at the base of the neck of the same.

The body portion 1 of the bottle is of oblong outline and the bottom is of depressed and inwardly-curved contour, as shown at 2.

A flat portion 3 is provided at the base of the neck of the bottle on the front and rear side, the flat portion extending upwardly, terminating in a curve which gradually inclines toward the center from the sides thereof. A shoulder is formed on the top of the body portion 1 by reason of the flat portion 3.

On the right and left hand sides of the bottle the base of the neck is of curved contour, forming a shoulder on these sides symmetri-

cal with that formed on the top of the front and back sides of the body portion 1.

The corners of the bottle are of beveled design, as shown at 4, and thereby obviating the sharp corners that would result in a bottle of this shape constructed with a sharp edge.

Another feature to which we wish to call particular attention is the shape of the oblong forming the body portion of the bottle. For example, in a quart bottle the oblong portion or body of the bottle will measure four and one-half inches width, two and three-fourths inches depth, and six and one-half inches length, and in larger or smaller bottles the proportion will be the same, the relative length equaling the relative width, and so on.

Having fully described our invention, what we claim as new is—

The design for a bottle having a neck with its sides and ends curved and ending in a shoulder, formed by the body, the body having beveled edges and ending in a bottom having an inwardly curved contour, as shown and described.

In testimony whereof we affix our signatures in presence of two witnesses.

FREDERICK C. RENZIEHAUSEN.
HENRY SCHUETZ, JR.
